[57] ABSTRACT

[22] Filed: **Sept. 27, 1973**

An apparatus for physically reducing material in which a rotor is rotatable on the axis of a vertical housing. The inner wall of the housing is in the form of axial wear plates which have side edges engaging carrier members in the housing. The rotor has a plurality of rows of disc-like beating members thereon at different levels with each beating member having a profiled periphery protruding radially from the rotor for cooperation with the wear plates. The gap between the peripheral portions of the beating members and the inside of the housing decreases in the downward direction. Material to be reduced is fed into the housing at the top and progressed downwardly therein while being reduced between the beating members and the wear plates.

DEVICE FOR CRUSHING SOLID MATERIALS

The present invention relates to a device for crushing solid materials such as light scrap, pre-cut light scrap, bulky waste, house waste, industrial scrap, old tires, synthetic materials, wood and paper, in which in a housing on a rotor with vertical axis of rotation there are arranged beating members which are located in a plurality of steps one above the other and distributed uniformly over the circumferences of said rotor. These, 10 beating members are in disk form and are freely rotatable about vertical axes while having their circumferential area provided with profiles. The flight circles of said beating members, together with the inner wall of the housing or the profiled wearing plates connected to the inner wall of the housing, generate an annular gap which in steps decreases downward and through which passes the material to be crushed in a downward direction.

A device of this type has become known in which a 20 rotor is arranged in a housing which conically decreases in downward direction and which in a plurality of steps arranged one above the other and within the steps has uniformly distributed over the circumference a plurality of disk-shaped beating members of uniform diameter which are freely rotatable with great play about vertical axes. The flight circles of the beating members arranged in steps one above the other are of the same size and together with the downwardly narrowing housing confine an annular gap which narrows in steps in downward direction, and through which the material to be crushed passes in downward direction.

This heretofore known device has the drawback that the inner chamber, in case of the rotor being blocked, is accessible only under difficulties, and that the change of the profiled bearing plates which are connected to the inner wall of the housing by screws is time-consuming, in view of the great number of screws of the wearing plate connection and the connection of the detachable part of the housing wall. Moreover, the working edges of the wearing plates can be used only in one 35 rotary direction.

It is, therefore, an object of the present invention, with a device for crushing solid materials of the above-mentioned type, to improve the accessibility toward the interior of the housing, while maintaining the annular gap which is located between the flight circle of the disk-shaped beating members and the profiled wearing plates connected to the housing.

It is also an object of this invention to provide a device as set forth in the preceding paragraph in which the exchange of wearing plates is simplified and the useful life span of the wearing plates is increased.

These and other objects and advantages of the invention will appear more clearly from the following specification in connection with the accompanying drawings, in which:

FIG. 1 is a vertical partial section through a device, according to the present invention, for crushing solid materials with a vertical rotor shaft, said section being taken along the line I—I of FIG. 2.

FIG. 2 illustrates, on a larger scale than FIG. 1, a horizontal section taken along the line II—II of FIG. 1.

FIG. 3 illustrates, on a larger scale than FIG. 2, that portion of FIG. 2 which is encircled by a dot-dash circle III.

FIG. 4 is a top view of a detail of FIG. 1.

The device according to the present invention is characterized primarily in that the inner wall of the housing is composed of a plurality of vertical wearing plates which are provided with working edges on one or both sides, each of said wearing plates being adapted in a positive manner to be placed between two adjacent profiled carriers, which are stationarily arranged and have the shape of a polygon, and is furthermore characterized in that the flight circles of disk-shaped beating members, which are arranged in a plurality of steps one above the other in a rotor and are freely movable about vertical axes, increase in size from step to step in downward direction in uniform or non-uniform steps.

In order to obtain a positive connection between the stationarily arranged profiled carriers and the wearing plates, it is provided that the wearing plates have their narrow sides provided with V-shaped guiding grooves. For purposes of avoiding soiling and damage to the guiding means between the profiled carriers and the wearing plates during the operation of the device, it is furthermore provided that the play between the guiding surfaces of the stationary profiled carriers and the guiding surfaces of the V-shaped guiding grooves of the wearing plates is adapted to be eliminated by clamping means operable by pressure fluid means and arranged in those guiding surfaces of the profiled carrier which face away from the interior of the container. In order to realize a maximum use of the wearing plates, it is provided according to the invention that the profile on the working surface of the wearing plates is provided symmetrically with regard to the longitudinal axis of the wearing plates.

The adjustment of differently great flight circle diameters of the disk-shaped beating members, which are movably connected between carrier disks arranged in a plurality of steps one above the other and connected to the rotor, is effected in such a way that the vertical axes for the movable connection of the disk-shaped 40 beating members are connected in the carrier disks on pitch diameters of the same size, while the outer diameters of the disk-shaped beating members have the same size for one and the same step but vary in size from step to step.

Referring now to the drawings in detail, it will be noted that a cage-shaped frame is connected to the horizontal flange surface 2 of the lower machine part 1. This frame is composed of the lower flange 3, the lower bandage 4, the upper bandage 5, and a number of vertical profiled carriers 6 which are uniformly distributed over the circumference and are connected to the inner side of the annular bandages 5, 6. Between each two profiled carriers, wearing plates 7 are positively insertable, which plates extend approximately over the entire height of the profiled carriers. In this way a positive connection with V-shaped grooves on the two narrow sides of the wearing plate 7 and corresponding V-shaped profiles of the vertical profiled carriers 6 is established. For purposes of facilitating the assembly and disassembly, the wearing plates have their end faces provided with thread into which annular eyes 8 are screwed.

As will be evident from FIG. 2, the inner chamber of the container which is confined by the wearing plates 7 has the cross-section of a regular polygon. Centrally arranged in the interior of the inner chamber formed by the cage 4, 5, 6 and the wearing plates 7 with the work-

ing surfaces 7a is a rotor 9. Rotor 9 has a vertical axis of rotation and is adapted to be driven by an electric motor 30 through a transmission, for instance belt transmission, in both directions of rotation, said transmission being located in the lower part 1 of the machine.

The rotor 9 comprises a central tube 10 which is firmly connected to a shaft 40 journalled in the lower portion 1 of the machine. A plurality of carrier disks 11 are connected in steps of equal size and in horizontal arrangement one above the other. Connected to said carrier disks on uniform pitch circles, and uniformly distributed over the circumference, there is a plurality of vertical axes 12.

On these axes 12, disk-shaped beating members 13 are freely movably connected, which means are rotatable with considerable play. The disk-shaped beating members 13 always have the same outer diameter between each two adjacent carrier disks 11. The outer diameters of the disk-shaped beating members 13 are for the individual superimposed stages so selected that the flight circles defined by the rotation of the rotor 9 increase in downward direction, which means that the remaining gap between the flight circles or flight paths of the beating members 13 and the vertical wearing plates 7 become narrower in downward direction. The decrease in the gap in downward direction may either be in uniform steps or in adaptation to the specific properties of the material to be crushed, or also in non-uniform steps to be ascertained by tests. The circumference of the disk-shaped beating members 13 may be provided with different types of profiles, for instance, with rough teeth. Furthermore, the disk-shaped beating members 13 may have their circumference designed so as to have the form of a regular polygon.

The upper ends of the vertical profiled carrier 6 are provided with ribs or fins 14 which point radially toward the interior of the container. Connected to said ribs 14 is a cylindrical collar 15, the outer diameter of which is so selected that the wearing plates 7 when being removed will not abut in upward direction. A filling funnel 16, which by means of its collar 17 rests on the collar 15, extends into the collar 15, said funnel 16 being rotatable and removable.

Within the inclined portion of the filling funnel 16 there is provided a flap 18 which closes almost the entire inlet cross-section and which has its upper end journalled by means of a joint 19. The flap 18 is by means of abutment 20 prevented from escaping against the flow direction of the inflowing material to be crushed. For purposes of pre-crushing the material to be crushed which impacts from above of the rotating rotor 9, there is above the uppermost carrier disk 11 a beating arm 21 provided, which is firmly connected to the rotor 9 and which is illustrated as an individual part in FIG. 4. The beating arm 21 is provided with two radially extending and exchangeable beater plates 20, and thus is effective in both directions of rotation.

Below the lowermost carrier disk 11 there are provided two radially extending pairs 23 of beater plates by means of which the material crushed and compacted in the space below the lower-most carrier disk 11 is centrifuged out of the outlet opening 24. The outlet opening 24, which tapers in a funnel-shaped manner, is symmetrically designed and is likewise effective in both directions of rotation of the rotor.

In order to avoid damage to the guiding surfaces of surfaces vertical profiled carriers 6 and to the wearing plates 7 inserted from above, and in order at the same time to prevent the escape of dust from the interior of the device, the wearing plates 7 are in their V-shaped guiding means held in such a way that the guiding surfaces facing toward the interior of the chamber firmly and tightly rest against each other. FIG. 3 diagrammatically shows a clamping device for clamping the wearing plates 7 together. According to this clamping device, there are provided pressure elements 25 which are movable in grooves provided in the guiding surfaces facing away from the inner chamber. These pressure members 25 are, by means of a hose 26 or thin-walled pipe, filled with pressure fluid pressed against the adjacent guiding surface of the wearing plates 7. An additional cover 27, which may be covered by noise-absorbing substances, is arranged on the outside of the bandages 4, 5.

The advantages realized according to the present invention consist primarily in that a removal of individual or a plurality of wearing plates will be possible in a minimum of time. This brings about a particularly economical operation of the device when the wearing plates are on both surfaces provided with working edges which are arranged symmetrically with regard to the longitudinal axis and which, in case of wear of one working surface, are removed and then reversed and reinserted. In this way the span of use of each individual wearing plate will be doubled. In view of the possibility of changing also the direction of rotation of the rotor, the working edges of each working surface can be used in both directions, whereby the span of use of the wearing plate is again doubled.

A further advantage of the simple wearing plate in removal consists in that, in case the rotor should be blocked by jammed material in the interior of the device, the interior of the device will be easily accessible.

It is, of course, to be understood that the present invention is, by no means, limited to the specific showing in the drawings, but also comprises any modifications within the scope of the appended claims.

What is claimed is:

1. In an apparatus for physically reducing material; a housing substantially circular in cross section disposed on a vertical axis, axial wear plates distributed circumferentially inside said housing and forming the radially inner wall thereof, an axial corner extending along at least one circumferential edge of each wear plate, profiled carrier members on the housing interposed between and extending axially along said wear plates, interfitting elements of key means on the sides of said carrier members and the edges of said wear plates for supporting said wear plates in said housing, a rotor in the housing rotatable on the axis of the housing, and axially spaced rows of circumferentially spaced disc-like beating members on said rotor, means supporting each beating member for rotation on a vertical axis on the rotor, each beating member having a profiled peripheral portion protruding radially from the rotor, the radial gap between the radially inner wall of said housing and the periphery of each said row of beating members decreasing in the downward direction.

2. An apparatus according to claim 1 in which said rotor is substantially cylindrical and the beating mem-

bers increase in diameter from the top of the rotor to the bottom of the rotor.

3. An apparatus according to claim 1 in which said elements of key means comprise grooves extending along the side edges of the plate and rib portions on said carrier members receivable in said grooves.

4. An apparatus according to claim 1 in which said wear plates are parallel to the axis of the housing, said rotor being cylindrical, and said beating members increasing in diameter from the top of the rotor to the bottom of the rotor to obtain the narrowing of the gap between the rotor and the housing in the downward direction.

5. An apparatus according to claim 1 in which said elements of key means comprise grooves extending along the side edges of the plate and rib portions on said carrier members receivable in said grooves, and clamp means operatively interposed between said carrier members and wear plates and clamping the wear plates in radially outermost positions on said carrier members.

6. An apparatus according to claim 5 in which said clamp means comprise fluid pressure expansible means interposed between the radially outwardly facing side of said ribs and the radially inwardly facing sides of said grooves.

7. An apparatus according to claim 1 in which said means supporting said beating members on said rotor comprises vertical shafts in the rotor.

10 8. An apparatus according to claim 7 in which all of the beating members in each row thereof are the same diameter.

9. An apparatus according to claim 1 in which said means supporting said beating members on said rotor comprises a plurality of vertical shafts in the rotor all on a common pitch circle and all of the beating members in a respective row being of the same diameter.

15 10. An apparatus according to claim 3 in which each said carrier member and each said wear plate is symmetrical about a respective axial plane of the housing.
